EMERGENCY BRAKE.

(Application filed Nov. 29, 1897.)

(No Model.)

UNITED STATES PATENT OFFICE.

GRIFFITH JOHN, OF YONKERS, NEW YORK, ASSIGNOR, BY MESNE ASSIGNMENTS, TO THE OTIS ELEVATOR COMPANY, OF EAST ORANGE, NEW JERSEY.

EMERGENCY-BRAKE.

SPECIFICATION forming part of Letters Patent No. 665,225, dated January 1, 1901.

Application filed November 29, 1897. Serial No. 660,101. (No model.)

To all whom it may concern:

Be it known that I, GRIFFITH JOHN, a subject of the Queen of Great Britain, residing at Yonkers, in the county of Westchester and State of New York, have invented certain new and useful Improvements in Emergency-Brakes, of which the following is a specification.

Elevator apparatus have from time to time been supplied with automatic safety brakes or devices of various different constructions, some of which have proved to be exceedingly efficient, so that serious accidents where such devices have been employed are almost unknown. It is desirable, however, to prevent the conditions under which such devices come into action.

The well-known automatic devices for throwing in the safeties are dependent upon the velocity at which the car travels, and as the ordinary running speed of elevators in the modern office buildings is so great it is desirable that some device should be made to enable the operator in the cage, in case of any derangement of the machinery or from other causes, to lock the cage to the guides before the speed of the car attains sufficient velocity to throw in the automatic devices, and it is also desirable that these devices be of such construction that the operator can release the grips and lock them again at will, thus enabling the operator to bring the car to the landing, so as to discharge the passengers, thereby preventing the destruction of the closure or the car and relieving the passengers from an annoying and disagreeable position.

My invention consists in means for securing said results.

In the accompanying drawings, Figure 1 illustrates in elevation sufficient of an elevator apparatus to show one means of carrying out my invention. Fig. 2 is a sectional plan of the cage inverted with the parts illustrated in Fig. 1. Fig. 3 is an enlarged longitudinal section of part of the braking devices, and Fig. 4 is a plan of Fig. 3.

While my improvement may be carried out in connection with automatic safety devices of different constructions, I have illustrated it in the drawings in connection with one of

the most effective constructions now in practical use and in which the brake devices are arranged upon a beam B, which may extend above the roof or, as shown, may be beneath the bottom of the car A. There are two brakes M M, one for gripping each of the guides X, and each consisting of two jaws 3 3, pivoted at x and caused to bite the guide by the separation of their inner ends on the straightening of toggles g, as results if the suspension-cables break or are slackened and the car descends by gravity too rapidly.

There is a drum I, around which is wound a cable C, passing around a pulley 5 and connected to an endless cable C', which passes at the top around a pulley F of a governor and at the bottom around a pulley F', which is weighted to keep the cable C' taut. The drum I is connected to the two pairs of toggles through the medium of shafts J J, each of which is reversely threaded at opposite ends, one end extending into the threaded socket of a box 6, connected with the toggle g, and the other into the threaded socket of a box 7 upon a threaded shaft J', carried by the drum I.

So far as the general arrangement above described is concerned, the construction and operation do not materially differ from that set forth in the patent to A. C. Ellithorpe, No. 376,374, dated January 10, 1888. As in the apparatus in the Ellithorpe patent, any undue speed of the cage will throw out the governor-balls, arrest the movement of the cable C', and drawing upon the cable C will rotate the drum and its boxes, thrust outward the rods or shafts J J, and apply the brake. In the present construction, however, the arrangement of the shafts J and their threaded ends and the boxes 6 7 is somewhat different from that in the Ellithorpe patent, so that each shaft J is so mounted that it can be turned independently upon its axis whether the drum I is in motion or not, and the rotation of the shafts with reverse threads at the opposite ends will serve as a means of separating or bringing together the boxes 6 7 and of applying or loosening the brakes. Different means may be employed for rotating the shafts J from within the cage by the operator. Preferably both shafts should be turned together

simultaneously, and to this end I provide each shaft J with an arm 10, connected by a rod 12 with an arm 14 on a shaft 13, suspended by brackets below the bottom of the cage, and from the shaft a hand-lever 15 is extended upward through the bottom of the cage into the latter. It will be evident that whether the drum I is stationary or has started in movement owing to the stoppage of the traveling cable C' the operator can by swinging the lever 15 turn the shafts J, and thereby quickly thrust the latter outward longitudinally and apply the brakes, and thereafter by a reverse movement of the lever release them. It will be evident that while the brakes may thus be quickly applied they are not caused to grasp the guides so suddenly as to bring the cage to an instant stop, which would be more destructive in many instances than a continued movement. The operating device within the cage is preferably in the form of a lever adapted to be operated by hand to either apply or release the brakes positively, as may be required; but in some instances the operating device may be arranged to be operated by the foot.

Without limiting myself to the precise construction and arrangement shown, I claim as my invention—

1. In an elevator-car brake, the combination of a car, a suspension-cable therefor, braking device, automatic operating devices therefor independent of the suspension-cable, and an operating device within the car where-
30 by the operator can operate the braking de-
vice to positively apply or release the latter
35 to regulate the speed or arrest the motion in-

dependently of the automatic devices, sub-
stantially as described.

2. In an elevator-car brake, the combina- 40
tion with the car, its suspension-cable, clamps,
operating-shaft, and automatic operating de-
vices independent of the suspension-cable,
of an operating device within the car, and
connections between the latter and said shaft, 45
whereby the operator can positively apply or
release said clamps independently of the au-
tomatic devices, substantially as described.

3. In an elevator-car brake, the combina- 50
tion with the clamps, toggles, threaded oper-
ating-shafts, drum, and means for automati-
cally operating the drum, of an operating-
lever within the car, and connections between
the lever and said shafts whereby the oper- 55
ator may turn the shafts independently of the
drum to positively apply or release the
clamps, substantially as described.

4. In an elevator-car brake, the combina- 60
tion with the clamps, toggles, threaded shafts,
drum, and boxes 6 and 7 connecting the
shafts, of automatic actuating devices and a
pivoted operating-lever within the car, arms
on said shafts, and connections between said 65
arms and lever, whereby the operator may
operate the shafts independently of the drum
to apply or release the clamps, substantially
as described.

In testimony whereof I have signed my
name to this specification in the presence of
two subscribing witnesses.

GRIFFITH JOHN.
